UNITED STATES PATENT OFFICE.

THEODORE KIRCHEN, OF CHICAGO, ILLINOIS.

DESIGN FOR A NOVELTY-BASKET.

55,055.

Specification for Design.

Patented May 4, 1920.

Application filed August 27, 1919. Serial No. 320,314. Term of patent 3½ years.

To all whom it may concern:

Be it known that I, THEODORE KIRCHEN, a citizen of the United States, residing at Chicago, in the County of Cook, State of Illinois, have invented a new, original, and ornamental Design for a Novelty-Basket, of which the following is a specification, reference being had to the accompanying drawing, in which a perspective view of the design is shown.

I claim:—

The ornamental design for a novelty basket, as shown.

In testimony whereof I affix my signature.

THEODORE KIRCHEN.
